T. W. SMALL.

OVERHEAD ELECTRIC CONTACT.

APPLICATION FILED JUNE 26, 1908.

937,107.

Patented Oct. 19, 1909.

UNITED STATES PATENT OFFICE.

THOMAS W. SMALL, OF CLEVELAND, OHIO, ASSIGNOR TO THE ACME AUTOMATIC STREET INDICATING COMPANY, OF CLEVELAND, OHIO, A CORPORATION OF OHIO.

OVERHEAD ELECTRIC CONTACT.

937,107.

Specification of Letters Patent. Patented Oct. 19, 1909.

Application filed June 26, 1908. Serial No. 440,473.

To all whom it may concern:

Be it known that I, THOMAS W. SMALL, a citizen of the United States, residing at Cleveland, in the county of Cuyahoga and State of Ohio, have invented a certain new and useful Improvement in Overhead Electric Contacts, of which the following is a full, clear, and exact description, reference being had to the accompanying drawings.

10 The object of this invention is to provide a very simple and efficient overhead contact station for trolley roads where it is desired to establish an electric circuit at predetermined intervals along the right of way.

15 My contact device is supported by the supporting wires for the trolley wire and is located at intervals according to the stops to be made, and may operate to close a circuit, operating, for example, a suitable 20 street indicator on the car. This circuit closing station may be used for other purposes, if desired. It is adapted, in the form shown, to be connected with the trolley circuit and to coöperate with a metallic sleeve 25 on the trolley pole which forms one terminal of a suitable circuit.

The drawings clearly illustrate my invention, wherein—

30 Figure 1 is an elevation, partly sectional, of the contact station; Fig. 2 is a vertical central section thereof showing the position the trolley pole occupies in passing through the station; Fig. 3 is a side elevation of one of the insulators for holding the station rigidly to the guy wire; Fig. 4 is an elevation of the inner end of one of the blocks which carries the contact brushes; Fig. 5 is a cross section through the trolley pole, showing my metallic contact sleeve thereon.

40 As shown in the drawings, 10 represents the guy wire which is adapted to support the trolley wire 11 by means of the usual insulated construction. This construction as shown, includes the supporting member 12 to which the trolley wire is soldered, the stud 13 screwing into such member, the upper insulator 14 which carries such stud, and the lower insulator 15 which surrounds the stud and interlocks with the upper insulator, and finally the supporting yoke 16 which occupies the groove between the two insulator sections, and has arms 17 which overhang the guy wire. This is a usual form of construction and need not be further described.

55 The frame of my contact station consists

of a flat U-shaped plate 20. This plate is primarily held by being mounted between the lower end of the lower insulator 15 and the upper end of the trolley wire support 12. The plate is provided with an opening 60 through which the stud 13 extends and is clamped between the support and insulator. The plate bears directly on the wire support and is thus in electric connection with the trolley wire.

65 The plate 20 is prevented from turning around on the stud 13 as an axis by reason of one or more clamps, holding the plate to the guy wire. Two of these clamps are shown, each consisting of a pair of insulating blocks 70 21 and 22 surrounding the guy wire and held thereto by a suitable wire 23, the intermediate portion of which lies beneath the plate 20 and which passes in a loop upwardly through openings in that plate and through 75 two openings in the blocks 21 and 22, the upper ends of the wire being twisted together. It will be seen from this construction that the plate 20 is rigidly held in position extending transversely of the trolley 80 wire and depending on opposite sides thereof, that it is insulated from the guy wire, and is in direct electric connection with the trolley wire.

85 Secured to each of the depending portions of the plate 20 on the inner side thereof is the wooden block 30, each of which carries inwardly projecting wires or strips 31. These inwardly projecting metallic bristles, so to speak, are preferably flat narrow strips 90 and are bent into U-shape, and several of them nest within each other, as shown in Fig. 1. Extending crosswise of the innermost strips in each nest of metallic bristles is the tie wire 32. This wire lies on the outer face of the block 30 and is in electrical engagement with each of the various sets of strips, as shown in Fig. 4. This block is held tightly against the plate 20 by the bolts 34, and the nuts thereon and in such position holds the wire 32, as well as the outermost of the metallic strips in close physical contact with the inner surface of the plate 20. The wire 32 performs the double function of holding the various sets of bristles securely in the wooden block 30 and of making a good electric contact between all of the bristles and the plate 20. Each of the metallic bristles being in good electrical connection with the plate 20 and thus with the trol- 110

ley wire, it results that if anything metallic passes between the two sets of metallic bristles, contacting with any of them, the same is electrically connected with the trolley wire.

5. The street indicator, or whatever device is employed on the trolley car, may have one terminal connected with the ground and the other with a conductor 40 extending upwardly within the trolley pole 41, in Fig. 2. Near the upper end of this trolley pole it is surrounded by an insulating sleeve 42, and around this sleeve is a metal sleeve 43 connected with the wire 40 which passes 15 through an insulating bushing in the pole and through the sleeve 42. The sleeve 43 is preferably split and is provided with a flange 44 which enables bolts to clamp it in place. This sleeve 43 is so positioned with 20 reference to the trolley wheel 45 that whenever such wheel passes along the wire, at one of my stations, the sleeve 43 will engage and make electrical contact with the bristles 31, while the wheel will ride through my station 25 above the bristles and out of contact therewith. The metallic sleeve is long enough and the parts are so positioned that this result will take effect irrespective of the angle at which the pole may be standing.
30. Practice has demonstrated that my station is very efficient in establishing a shunt from the trolley wire to mechanism on the car whenever one of the stations is reached, irrespective of sagging of wires, weather 35 conditions, speed of operation, or any of the other extraneous factors which tend to interfere with the production of satisfactory overhead contacts.

Having thus described my invention, I 40 claim:

1. In an overhead contact, the combination of a frame adapted to depend on opposite sides of the trolley wire, contact members carried by both portions of the depending frame projecting toward each other, said contact members consisting of narrow flat strips arranged in sets.
2. In an overhead contact, the combination of a frame adapted to depend on opposite sides of the trolley wire, contact members carried by both portions of the depending frame projecting toward each other, said contact members consisting of narrow flat strips arranged in sets, the members of each 55 set nesting within each other, and suitable retaining means for such nested sets.
3. In an overhead contact, the combination of a suitable U-shaped plate, wooden blocks secured to the inner sides of both depending members of the plate, and metallic bristles carried by the wooden blocks.
4. In an overhead contact, the combination of a U-shaped plate adapted to be in electric connection with the trolley wire and 65 clamped by the wire insulator, metallic con-

tact members carried by the inner sides of said plate near its lower ends and projecting inwardly.

5. In an overhead contact, the combination of a U-shaped plate adapted to be in electric connection with the trolley wire and supported by the wire insulator, metallic contact strips, wooden blocks in which said strips are secured, and means for holding said blocks to the inner sides of said plate near its lower ends with the strips projecting inwardly and in electrical connection with the plate.

6. The combination of a trolley wire, means for supporting the same, a frame 80 clamped between the trolley wire support and trolley wire and depending on opposite sides of the trolley wire, inwardly projecting metallic members carried by said frame, and a metallic sleeve on the trolley 85 pole adapted to engage such metallic members, while the trolley wheel is on the trolley wire.

7. The combination of a trolley wire, means for supporting the same, a suitably 90 supported metallic member, and a metallic sleeve on the trolley pole adapted to engage such metallic member, while the trolley wheel is on the trolley wire and irrespective of the angle the trolley pole may be occupying, said sleeve being longitudinally split and having projecting portions adjacent to the split, and securing means engaging such projecting portions whereby the sleeve may be removed.

8. In an overhead electric contact, the combination with a U-shaped plate, and a series of metallic bristles nested in sets and in electric contact with each of the depending arms of the plate.

9. In an overhead electric contact, the combination of a U-shaped plate clamped by the trolley hanger and having depending arms on opposite sides of the trolley wire, and two sets of metallic bristles adapted to be secured to the inner sides of said depending arms, and projecting toward each other into the path of the trolley pole.

10. In an electric contact, the combination of a supporting plate and a block carrying 115 nested sets of metallic bristles in electric contact with said plate.

11. The combination of a U-shaped metal plate, a wooden block secured to the inner face of each of the depending arms of the 120 plate, and a series of metallic bristles carried by each block.

12. The combination of a metal frame, a wooden block secured to the inner face of such frame, and a series of metallic bristles 125 carried by such block, said bristles consisting of U-shaped strips nesting within one another in several sets.

13. The combination of a frame, an insulating block held thereto, several sets of 130

strips nesting within one another and seated in said block, and a wire engaging several of such sets and serving to hold the bristles in the block, and also insure good electric connection with the frame.

14. The combination of a U-shaped metal plate, a wooden block secured to the inner face of each of the depending arms of the plate, a series of metallic bristles carried by each block, said bristles consisting of U-shaped strips nesting within one another, in several sets, and a wire engaging several of such sets and serving to hold the bristles in the block, and also insure good electric connection with the plate.

15. The combination of a depending frame adapted to be clamped between the insulator and supporting bar of a trolley hanger, and

an insulator carried by such frame and adapted to embrace the guy wire and thereby prevent displacement of the frame.

16. The combination with a trolley hanger including a wire support and insulator, of a U-shaped flat plate adapted to extend intermediately between the support and insulator and be clamped thereby, and an insulator mounted on the upper side of the intermediate portion of such plate and adapted to embrace the guy wire which supports the trolley hanger.

In testimony whereof, I hereunto affix my signature in the presence of two witnesses.

T. W. SMALL.
